UNITED STATES PATENT OFFICE.

HUGO BELZ, OF NEW YORK, N. Y.

VEST OR COAT FOR CARRYING SECURITIES.

Application filed December 5, 1921. Serial No. 520,144.

To all whom it may concern:

Be it known that I, HUGO BELZ, a citizen of the United States, residing at New York city, in the county of New York and State 5 of New York, have invented new and useful Improvements in Vests or Coats for Carrying Securities, of which the following is a specification.

This invention relates to vests or coats for 10 carrying securities, gems and other valuables, and the principal object is to produce a device of this kind which cannot readily be removed from the person of the wearer.

Another object is to produce a garment of 15 this nature having appearance of an ordinary vest and constructed with interlinings of hardened steel mail.

Another object is to provide simple and efficient locking means.

With these and other objects in view, the invention resides in certain novel construction and combination and arrangement of parts, the essential features of which are hereinafter fully described, are particularly 20 pointed out in the appended claims, and are illustrated in the accompanying drawing, in which:—

Figure 1 is a view of the vest with the fastening devices opened.

Figure 2 is a sectional view taken substantially on line 2—2 of Figure 1.

Figure 3 is an enlarged detached view of the four fastening strips.

Figure 4 is a detail horizontal sectional view taken through the locking means.

Like characters of reference refer to like parts in all views.

Referring to the drawing in detail, it will be seen that I have provided a vest which 40 is constructed with an inner lining 10 of cloth and an outer fabric layer 11 both of which may be any usual suitable material for such garments. Between the two layers I provide two layers of hardened steel chain 45 or spiral armor indicated at 12 and 13 which merge into a single layer 14 at approximately the chest line and this single layer 14 passes over the shoulders and down in the back where it is again coupled to the two 50 layers 12 and 13. The two layers 12 and 13 are fastened together at their lower edge thereby forming a pocket 15 which extends completely around the body and may be provided with a lining at 16 and 17 of chamois 55 or any other suitable material.

It is intended that in use the valuables

shall be placed within the pocket 15 and then the edges of the same secured together and locked so as to prevent thieves from snatching the valuables or in case of a hold-up, to prevent the ready removing of the garment from the wearer by shears or other cutting means.

The locking means comprises four hardened steel bars numbered respectively 18 and 19 on the right hand side of the vest and 20 and 21 on the left hand side of the vest. The members are all slightly rounded on the edges so as to prevent cutting material, and are covered with any desired fabric. The edges of the lining 12 are secured respectively to members 18 and 20 while those of the outer layer of armor 13 are secured respectively to the members 19 and 21. Member 18 is provided with a plurality of studs 22 which are undercut so as to have enlarged heads. Members 19 and 20 are provided with apertures 23 of a size slightly larger than the heads of members 22 so that they may readily pass thereover, the 80 apertures 23 being made to register perfectly with the position of the studs 22. The member 21 is provided with a plurality of key hole slots 24 the enlarged portions of which will pass over the heads of studs 22 and the restricted portions of which are adapted to engage with the shank of the studs 22 when member 21 is moved downwardly. All four of the plates have near 90 their bottom apertures 25 for the reception of the tongue of a lock.

In operation, after the jacket has been placed on and the valuables placed in the pocket 15, member 20 is brought with its apertures 23 into engagement with the studs 22 of member 18. Then member 19 has its apertures 23 engaged with the studs 22, and finally the large portions of the slots 24 in member 21 are passed over the heads of studs 22, and member 21 is moved downwardly to lock the four of the bars together. A lock is then inserted in the registering apertures 25 and secured in place.

It will be seen that in this manner I have constructed a garment for carrying securities and other valuables which may not be readily removed from the body of the wearer either by the use of a cutting instrument or by stripping the same over the head, as the steel will not give sufficiently to permit of removal in the last mentioned manner. When it is used by messenger boys be-

tween banks and the like the garment may be locked on the messenger by the official in one bank and unlocked by the official in the receiving bank.

5 While I have described what I deem to be the most desirable embodiment of my invention, it is obvious that many of the details may be varied without in any way departing from the spirit of my invention, and 10 I therefore do not limit myself to the exact details of construction herein set forth, nor to anything less than the whole of my invention limited only by the appended claims. What is claimed as new is:—

15 1. A garment of the class described, the combination of the usual outer and inner layers of fabric, a double layer of flexible

metal forming a pocket encircling the body, a single layer of flexible metal supporting 20 said pocket from the shoulders, and a plurality of steel plates co-active with each other for securing and locking said pocket in closed condition.

2. A garment of the class described, the combination of the usual outer and inner layers of fabric, a double layer of flexible 25 metal forming a pocket encircling the body, a single layer of flexible metal supporting said pocket from the shoulders and means at the mouth of said pocket for securing and 30 locking the same in closed condition.

In testimony whereof I have affixed my signature.

HUGO BELZ.
